DISPENSING DEVICE

Charles Stern, Jersey City, N. J.

Application May 28, 1942, Serial No. 444,853

8 Claims. (Cl. 221—47.1)

This invention relates to dispensing devices. It is particularly directed to devices for dispensing grease and the like material.

One object of this invention is to provide a pump of the character described, including a tank, said pump being so constructed that no excessive pressures will be built up within said tank during the pumping operation.

A further object of this invention is to provide a pump of the character described, comprising a tank to contain the grease to be pumped, and a piston within the tank adapted to be moved by a screw, the piston and screw being attached to the head of the tank, and said head together with the screw and piston being removable as a unit from the tank, whereby to facilitate quick refilling of the tank with grease.

Another object of this invention is to provide a pump of the character described, provided with improved means to permit the pump to be carried by two men, and also provided with means whereby the pump may be actuated manually by either one or two persons.

Still a further object of this invention is to provide in a pump of the character described, means to disconnect the pump actuating means when the tank is substantially empty.

Yet a further object of this invention is to provide a pump of the character described, comprising a tank having a head at one end and quickly detachable means to fix the head to the tank, whereby the head may be quickly removed so as to permit quick refilling of the tank.

A still further object of this invention is to provide a pump comprising a tank, a removable head at one end of the tank, an outlet at the other end of the tank, a piston within said tank, a gear pump on said head having its inlet end connected to the outlet end of the tank, means to simultaneously move the piston downwardly in the tank and operate the gear pump, said head, piston and gear pump being detachable from the tank and movable as a unit off the tank, whereby to entirely uncover the tank to facilitate refilling thereof, and also to permit said head, piston and gear pump to be quickly mounted on another tank which has been refilled with grease.

Yet another object of this invention is to provide a strong, durable and rugged tank of the character described, which shall be relatively inexpensive to manufacture, easy to manipulate and assemble, and yet practical and efficient to a high degree in use.

Other objects of this invention will in part be obvious and in part hereinafter pointed out.

The invention accordingly consists in the features of construction, combinations of elements, and arrangement of parts which will be exemplified in the construction hereinafter described, and of which the scope of application will be indicated in the following claims.

In the accompanying drawings, in which is shown one of the various possible illustrative embodiments of this invention,

Fig. 1 is a side elevational view of a pump embodying the invention; with parts broken away and in cross-section;

Fig. 2 is a top plan view of the tank shown in Fig. 1;

Fig. 3 is a side elevational view of the gear pump with parts broken away and in cross-section;

Fig. 4 is a cross-sectional view taken on line 4—4 of Fig. 2;

Fig. 5 is a cross-sectional view taken on line 5—5 of Fig. 1;

Fig. 6 is a cross-sectional view taken on line 6—6 of Fig. 1;

Fig. 7 is a side elevational view of the piston safety device; and

Fig. 8 is a partial side elevational view of the dispensing device illustrating one of the handles for carrying the same.

Referring now in detail to the drawings, 10 designates a dispensing device embodying the invention. The same comprises a tank 11 connected by pipe 12 to a gear pump 13. The tank 11 comprises an annular bottom member 14 formed with an annular groove 15 in its upper surface to receive the lower edge of a cylinder 16. The bottom member 14 is formed with a cored passage 17 leading to a radial nipple 18 at one side. The cored passage 17 extends to the center of the upper surface of member 14 and hence communicates with the interior of the tank. Said member 14 is furthermore formed with a plurality of equiangularly spaced radial ears 19, formed with vertical through bolt openings 19a. Member 14 is shown in the drawings to be formed with six ears 19, although any suitable number may be provided.

Surrounding the cylinder 16, below its upper end, is an annular ring 20. The ring 20 may be formed of two similar, symmetrical half rings 21, having meeting apertured ears 22, attached together by bolts 23.

Ring 20 is formed with a plurality of equiangularly spaced projections or ears 20, vertically

aligned with the ears 19 and likewise formed with vertical bolt openings 31. Extending through the openings 19a and 31 are vertical tie rods or bolts 33. At the lower ends of rods 33 are nuts 33a contacting the underside of ears 19. At the upper end of said rods are nuts 31a on opposite sides of ears 30. Thus rods 33 firmly interconnect the ring 20 with the bottom member 14.

Ring 20 is furthermore formed with a plurality of equiangularly spaced pairs of radial ears 35 formed with horizontal through openings 35a carrying transverse pivot pins 36. In the drawings, there is shown four pairs of ears 35, although any suitable number of such pairs of ears may be employed. Pivoted to each pivot pin 36 is a bolt 37 having an eye portion 37a, to receive the pivot pin. The bolts 37a are for the purpose of clamping to the top of the tank, a head 40 to be described in detail hereinafter. Screwed to the bolts 37a are wing nuts 38 engaging said head, as shown in the drawings.

The head 40 comprises a top plate 41 formed with an annular groove 42 on the underside thereof, receiving the upper end of cylinder 16. Plate 41 is formed with a plurality of radial notches 43 aligned with the bolts 37, and adapted to receive said bolts when said bolts are swung upwardly into the position shown in Fig. 1 of the drawings. In such position, the wing nuts 38 may be screwed down against the upper surface of said plate to firmly clamp the head 40 to the ring 20 and to the top of cylinder 16.

Plate 41 is formed with a central axial bearing opening 44 and journaled therein is an axial screw 45 extending downwardly into the tank to substantially the lower end thereof. The lower end of the screw 45 is journaled in a cross head 46. The outer ends of the cross head 46 are attached to the plate 41 by vertical, parallel tie rods 47 extending through openings 48 in said top plate. Within the tank is a piston 50 having internal screw threads 51 receiving the threads of the axial screw 45. The tie rods or bolts 47 pass through openings 52 in the piston. Packing glands 53 may be provided for the openings 52 to prevent leakage of grease through said openings. The piston 50 may be provided with a leather or other flexible liner 51 to contact the inner surface of the cylinder 16.

It will now be understood that rotation of the screw 45 will cause vertical movement of the piston. As the piston moves down, grease beneath the piston is pushed out through the passage 17. Attached to screw 45 are collars 60 disposed on opposite sides of the plate 41. Said screw has an upwardly extending portion 61 formed at its upper end with a polygonal head 62 to receive a wrench for turning the screw, for the purpose hereinafter appearing. Mounted on portion 61 of the screw is a worm wheel 63 for the purpose hereinafter appearing.

Mounted on top plate 41 and pivoted thereto about a vertical axis, as by screws 68, is a member 70 having a pair of spaced, parallel, upstanding ears 71 formed with aligned bearings in which is journaled a horizontal shaft 72. Fixed on the shaft 72 and disposed between the upstanding ears 71 is a worm 74 adapted to mesh with the worm wheel 63. At the outer end of shaft 72 is a polygonal head 74a adapted to receive a crank for turning said shaft. Fixed to said plate 41 is a Z-shaped guide bracket 75 which may be attached to said plate by one of the bolts 47. The bracket 75 has an arm 76, overlying a portion of member 70.

Means is provided to disengage the worm 74 from the worm wheel 63 when the tank is nearly empty. To this end, the free end of member 70 is connected by a coil tension spring 77 to a pin 78 fixed to the plate 41. The spring 77 tends to rotate member 70 in a clockwise direction looking at Fig. 2 of the drawings to disconnect worm 74 from the worm wheel 63.

Means is provided to hold member 70 in worm engaging or operative position. To this end, plate 41 is formed with a screw threaded opening 80. Screwed within said opening 80 is a tubular member 81 having a central apertured bottom wall 82. Extending through the aperture in the bottom wall 82 is a rod 83 having an enlarged head 84 at its upper end adapted to project above the head 40 to engage member 70 and hold the worm 74 in engagement with the worm wheel 63. Interposed between the head 84 and the bottom wall 82 is a coil tension spring 85 to normally push the head 84, upwardly. A packing 86 may be incorporated into the bottom of the tubular member 81 to prevent leakage.

Screwed to the lower end of rod 83 is a vertical rod 90 passing through an opening 91 in the piston 50. A packing gland 92 may be provided to prevent leakage through the opening 91. At the bottom of rod 90 is a head 93 disposed somewhat above the cross head 46. When the piston reaches the head 93 it will pull down the rod 90 and hence the pin or head 84 to release member 70 to permit the spring 77 to pull said member into disengaging position. Thus, when the grease in the tank is nearly all pumped out, the piston can no further be moved downwardly.

Attached to the nipple 18 is a pipe 100, said pipe being connected by an elbow 101 to the vertical pipe 12 disposed alongside the tank 12. The pipe 12 terminates below the upper end of the tank, as at 103. Attached to the head 40 is a radial Z-shaped bracket 104 having an outwardly extending arm. Supported on said arm 105 is the gear pump 13. Said gear pump 13 may be of usual construction and comprises a casing 106, within which are rotatably mounted a pair of meshing gears 107 and 108. Attached to the bottom of the casing 106 is a downwardly extending inlet pipe 108 aligned with the pipe 12.

The lower end 109 of pipe 108 is adjacent the upper end 103 of the pipe 12. The adjacent ends of the pipes 12 and 108 are interconnected by a quickly detachable leakproof coupling sleeve 110. The sleeve 110 has external screw threads 111 at its opposite ends. Screwed to the screw threaded portions 111 at the opposite ends of the sleeve 110 are sleeves 112 having inwardly extending flanges 113 loosely receiving the pipes 12 or 108.

Slidably mounted on the outer ends of sleeves 110 and disposed within the sleeves 112 are rings 114 having inwardly extending flanges 115 contacting the inner surface of the flanges 113. The sleeve 110 is formed at the opposite ends thereof with conical inner surfaces 117 fitted within which are rings 118 of rubber or other compressible material.

It will now be understood that when the sleeves 112 are tightened the rings 118 will be pressed against the pipes 12 or 108 to make a leakproof joint. When the upper ring 112 is loosened, and the wing nuts 38 are also loosened and the bolts 37 swung outwardly to disengage the head, said head together with the gear pump 13 and pipe 108 may be lifted off the tank, so that the tank will present a complete large opening to facilitate refilling the tank.

It will be noted that when the head 40 is lifted off the tank, the piston 59, screw 45, grease head 46 all come out with the head, as a unit.

In the drawings, numeral 108 designates the driving gear. The front and rear walls of the pump casing 106 are formed with bearing openings through which there extends a horizontal shaft 120 disposed on the axis of the shaft 72. At the outer end of shaft 120 is a polygonal head 121 to receive a handle for rotating said shaft. Shaft 120 is connected to shaft 72 by a universal joint 125. Universal joint 125 is located directly above the pivot 68 for member 70, so that member 70 together with shaft 72 may be swung about the axis of pivot 68. Any suitable rubber hose 126 may be connected to the exit end 127 of the gear pump 13.

The gear ratios of the gear pump relative to the piston and its operating gears is such that the gear pump will pump out grease as fast as grease is pressed out of the tank by the piston. With such construction, no internal pressures should build up within the tank, thus preventing buckling or damage to the tank and permitting the tank to be made of lighter materials.

When the worm 74 is disconnected from the worm wheel 63, a wrench or crank handle may be applied to the upper end 62 of the screw 45 so that said screw may be quickly rotated backwards to bring the piston up to the top again.

It will now be understood that the dispensing device may be operated either by one or two persons engaging either one or both of the ends 121 and 74 of the shafts 120 and 72.

Means is provided to permit the tank to be carried easily by two persons. To this end, ring 20 is provided with diametrically opposed pairs of ears 140. The ears 140 are disposed in a line at right angles to the shaft 72. Each pair of ears 140 carries a transverse horizontal pivot pin 141. Pivoted to each pin 141 is an elongated handle 142. Handles 142 may drop by gravity to hang adjacent the tanks. The handles may be lifted or swung outwardly to horizontal position, in which position, said handles will engage the underside of head 40. Each handle may be engaged by two hands of a person, and thus, the whole pump may be readily carried by two persons.

Although the pump may have a variety of uses, one contemplated use is to pump grease into gas mains on opposite sides of a break in the main which might be caused by bombing or in any other way. For this purpose it is necessary that the pump may be quickly carried to various places where pumping of grease is necessary, and the pump may be readily carried by the handles 142.

The head and gear pump 13 may be quickly disconnected from the tank so as to permit the tank to be refilled with grease. Furthermore, reserve tanks full of grease may be provided and when a tank is empty, the head may be quickly removed therefrom and inserted into another tank full of grease.

Another advantage of the pump disclosed herein is that no pressures are built up within the tank so that definite amounts of grease may be pumped and the grease will not continue to ooze out of the pump after the pumping operation stops, by reason of pressures built up within the pump as in prior devices.

It will thus be seen that there is provided a device in which the several objects of this invention are achieved, and which is well adapted to meet the conditions of practical use.

As various possible embodiments might be made of the above invention, and as various changes might be made in the embodiment above set forth, it is to be understood that all matter herein set forth or shown in the accompanying drawings is to be interpreted as illustrative and not in a limiting sense.

Having thus described my invention, I claim as new and desire to secure by Letters Patent:

1. In a dispensing device, a cylinder, a closure at one end of the cylinder, said cylinder having an outlet at its closed end, a head on the opposite end of said cylinder, means to detachably clamp the head to the cylinder, an axial screw journaled on said head and extending within said cylinder, axially thereof, a piston within said cylinder having threaded engagement with said screw, means on said head engaging said piston to prevent the piston from rotating relative to said cylinder, a pump on said head and connected to said outlet end of said tank, said head, pump, piston, screw and preventing means being removable as a unit from said cylinder upon disconnecting said head from said cylinder.
2. A dispensing device comprising a tank closed at one end and having an outlet at said end, a pipe communicating with said outlet, a head mounted on the opposite end of said tank, an axial screw journaled on said head extending into said tank, means to removably attach said head to said tank, a gear pump mounted on said head, a coupling interconnecting said pipe with the inlet end of said gear pump, and a piston within the tank having threaded engagement with said screw, said head and gear pump being removable from said tank and pipe upon disconnecting said head from said tank and loosening said coupling.
3. A dispensing device comprising a tank closed at one end and having an outlet at said end, a pipe communicating with said outlet, a head mounted on the opposite end of said tank, an axial screw journaled on said head extending into said tank, means to removably attach said head to said tank, a pump mounted on said head, a coupling interconnecting said pipe with the inlet end of said pump, a piston within the tank having threaded engagement with said screw, means to prevent rotation of the piston relative to said tank, said head and pump being removable from said tank and pipe upon disconnecting said head from said tank and loosening said coupling, and means to simultaneously operate said pump and rotate said screw.
4. A dispensing device comprising a cylinder, a bottom wall at the lower end of said cylinder having an outlet, a head on the upper end of said cylinder, an axial screw journaled on said head and extending into said cylinder, a piston having threaded engagement with said screw, means to prevent rotation of said piston within said cylinder, a member mounted on said head and pivoted thereto about an axis parallel to the axis of said cylinder, a shaft journaled on said member, a worm wheel on said screw and above said head, a worm on said shaft adapted to mesh with said worm wheel, a gear pump mounted on said head, means to connect said outlet with the inlet end of said gear pump, a shaft fixed to one of the gears of the gear pump, and a universal joint interconnecting said shafts, said universal joint being located in alignment with the pivot for said member, whereby said member and first shaft may be pivoted relative to the head and second shaft.

5. A dispensing device comprising a cylinder, a bottom wall at the lower end of said cylinder having an outlet, a head on the upper end of said cylinder, an axial screw journaled on said head and extending into said cylinder, a piston having threaded engagement with said screw, means to prevent rotation of said piston within said cylinder, a member mounted on said head and pivoted thereto about an axis parallel to the axis of said cylinder, a shaft journaled on said member, a worm wheel on said screw and above said head, a worm on said shaft adapted to mesh with said worm wheel, a gear pump mounted on said head, means to connect said outlet with the inlet end of said gear pump, a shaft fixed to one of the gears of the gear pump, a universal joint interconnecting said shafts, said universal joint being located in alignment with the pivot for said member, whereby said member and first shaft may be pivoted relative to the head and second shaft, and means on said shafts to be engaged by cranks whereby said shafts may be rotated by the use of two cranks.

6. A dispensing device comprising a cylinder, a bottom wall at the lower end of said cylinder having an outlet, a head on the upper end of said cylinder, an axial screw journaled on said head and extending into said cylinder, a piston having threaded engagement with said screw, means to prevent rotation of said piston within said cylinder, a member mounted on said head and pivoted thereto about an axis parallel to the axis of said cylinder, a shaft journaled on said member, a worm wheel on said screw and above said head, a worm on said shaft adapted to mesh with said worm wheel, a gear pump

mounted on said head, means to connect said outlet with the inlet end of said gear pump, a shaft fixed to one of the gears of the gear pump, a universal joint interconnecting said shafts, said universal joint being located in alignment with the pivot for said member, whereby said member and first shaft may be pivoted relative to the head and second shaft, means on said shafts to be engaged by cranks whereby said shafts may be rotated by the use of two cranks, and a pair of diametrically opposed handles on said tank disposed at right angles to said shafts.

7. A dispensing device comprising a tank having an outlet end at one end, a head at the opposite end of the tank, a gear pump on said head having its inlet end connected to the outlet end of the tank, a piston within the tank, and means on said head to move said piston longitudinally within said tank toward the outlet end of the tank to press material in the tank out through said outlet, and means to operate the gear pump to pump material passing through said outlet.

8. A dispensing device comprising a tank having an outlet end at one end, a head at the opposite end of the tank, a gear pump on said head having its inlet end connected to the outlet end of the tank, a piston within the tank, and means on said head to move said piston longitudinally within said tank toward the outlet end of the tank to press material in the tank out through said outlet, and means to operate the gear pump to pump material passing through said outlet, said head, piston, means and gear pump being removable from said tank as a unit.
